UNITED STATES PATENT OFFICE.

WALTON A. EDDY, OF RANDOLPH, NEW YORK.

SAND-BAND.

SPECIFICATION forming part of Letters Patent No. 635,467, dated October 24, 1899.

Application filed July 21, 1899. Serial No. 724,689. (No model.)

To all whom it may concern:

Be it known that I, WALTON A. EDDY, a citizen of the United States, residing at Randolph, in the county of Cattaraugus and State of New York, have invented a new and useful Sand-Band, of which the following is a specification.

This invention relates to vehicle-wheels, and more particularly to means for preventing access of sand to the bearings thereof. 10 The object of the invention being to provide attachments which will act to effectively prevent the ingress of sand at both the inner and outer ends of the wheel-hub.

A further object of the invention is to so 15 construct the attachments for this purpose that they may be readily applied and detached and in which the structure will be simple and cheap of manufacture and adjustable to wheels of usual structure.

20 In the drawings forming a portion of this specification, and in which similar numerals of reference designate corresponding parts in the several views, Figure 1 is a longitudinal vertical section of a wheel-hub and portions 25 of an axle and axletree, portions of the spindle of the axle and of the axletree being in elevation. Fig. 2 is a plan view of an axle with one element of the invention fixed thereto, a portion of said element being broken 30 away to show the formation of adjacent portions of the axle-spindle. Fig. 3 is a perspective view of one element of the invention, the parts thereof being shown slightly separated. Fig. 4 is a detail section of a modification 35 of the hub-retaining nut, showing its application to an axle-spindle and upon which the hub is mounted.

Referring now to the drawings, 5 represents an axle comprising a spindle 6, the rear end 40 of which latter is provided with an enlargement 7, which is substantially frusto-conical in form and peripherally of which is an annular groove 8, having grooves 9 leading therefrom in the direction of the outer end of the 45 spindle, an additional groove leading rearwardly from the groove 8 through the rear face of said enlargement. The spindle 6 is adapted to receive the hub 11 of a wheel comprising spokes 12, and which hub has in its 50 rear end an annular groove 13, adapted to receive the similar flange 14, which projects at

right angles to the face of a two-part sand-band comprising an upper element 15 and a lower element 16. The elements 15 and 16 have each a recess in their adjacent faces, 55 which are adapted to co-operatively form an opening for the reception of the outer end of the axle 5, adjacent the spindle, said elements 15 and 16, which are substantially semicircular in outline, being held in mutual engagement and tightly clamped upon the axle 5 through the medium of clamping-bolts 18, passed through ears 19, formed upon the elements 15 and 16 and having alining-perforations 20 therein for the reception of said bolts. 60 The bolts are provided with the usual retaining-nuts. The lower element 16 extends below the flange 14 and also below the recess 13 and forms, in effect, a drip flange or edge from which the sand, mud, and water may 65 drip, and thus be prevented from entering between the band and the hub. The upper element 15 of the band is provided with a rearwardly-directed lug 21, having a passage 22 therein, the upper end of which opens through 70 the upper face of the lug 21 and is provided with an encircling flange 23, forming, in effect, a tubular extension. The passage 22 extends downwardly and forwardly of the lug 21 and meshes with the rear end of the passage 24, above referred to, and which opens 75 into and extends rearwardly from the annular groove 8. Thus by contributing a lubricant to the passage 22 it will pass into the groove or passage 24 and thence to grooves 80 8 and 9, through which it will pass to the engaging portions of the bearing to lubricate 85 them.

Upon the axle 5 is fixed the usual axletree 25, held in place by means of the usual clips, 90 and which tree is terminated with a square shoulder at a point to directly impinge against the inner face of the lug 21. Pivoted to the lug 21 is a lever 26, having an annular flange upon its lower face adapted to receive the 95 flange 23 within its inclosure, and thus to prevent access of objectionable matter to the passage 22, the mutual engagement of the flanges preventing the movement of the lever upon its pivot when in its normal position. 100 The lever 26 has a rocking movement also upon its pivot to enable the end thereof to

be raised from the flange 23 when it is desired to expose the passage 22, and in order to hold the lever at different points in its lateral adjustment there is fixed in a recess in the adjacent end of the tree 25 a helical spring 28, which exerts an outward pressure upon the rear end of the lever and over which the lever may freely slide.

It will of course be understood that if desired a common form of oil-cup may be engaged with the upper end of the passage 22 for supplying a lubricant.

The outer end of the hub 11 is likewise provided with an annular groove 30, which is adapted to receive the inner edge of a cup-shaped sand-band 31, having a peripheral groove 32 therein for the reception of set-screws 33, passed through perforations in the band 34, of usual form, at the outer end of the hub, said band inclosing the wheel-securing nut 35 and having passed therethrough and centrally thereof a pivot-screw 36, which engages the center of the nut 35, and which screw may be adjusted to a position to receive the entire inward pressure of the hub or to distribute such pressure, as desired.

It will of course be understood that in practice the specific shape and construction of any part of the invention may be varied, and also that any desired material may be employed for any portion of the structure, without departing from the spirit of the invention. It will furthermore be seen that the sand-bands above described are applicable to any form of hub having the grooves in its ends, and also that the several parts of the invention may be easily and quickly adjusted, and that when thus adjusted they will act with efficiency.

In Fig. 4 of the drawings is shown a modification of the hub-securing nut, the web 40 of which is provided with an annular flange 41 at its periphery, which projects at right-angles to the plane of the web and is adapted to lie in the groove in the outer end of the hub in substitution of the sand-band 31, a second and concentric flange 42 lying within the inclosure of the first-named flange and being adapted to lie upon the opposite side of the flange 43, which forms a boundary for the groove in which the flange 41 is entered. It will be seen that in the employment of this nut it has the function of preventing access of sand to the spindle 6 in the same manner as does the sand-band 31.

Having thus described the invention, what is claimed is—

1. The combination with an axle comprising a spindle having an enlarged inner end provided with intersecting grooves, of a hub 60 mounted upon the spindle and having an annular groove therein, a sand-band provided with a flange adapted to enter said groove, an oil-passage formed in the band and communicating with one of the intersecting 65 grooves of the spindle, and a closure for said passage.

2. A sand-band comprising a two-part plate having an annular flange thereon, one of the parts of said plate extending beyond the flange to form a drip edge, a lug carried by the opposite part, and an oil-passage formed through said lug and opening through the opposite face of the plate.

3. The combination with an axle comprising a spindle having an enlarged inner end provided with intersecting grooves, of a hub 75 mounted upon the spindle and having an annular groove therein, a sand-band provided with a flange adapted to enter said groove, 80 said band extending below the flange to form a drip edge, an oil-passage formed in the band and communicating with one of the intersecting 85 grooves of the spindle, and a closure for said passage.

4. The combination with a hub having an outwardly-extending band at one end and provided with annular grooves in its ends, of an axle comprising a spindle having an enlarged inner end provided with intersecting grooves 90 and passed into the hub, a sand-band provided with a flange adapted to enter the groove in one end of the hub, said band extending below the flange to form a drip edge, an oil-passage formed in the band and communicating with one of the intersecting 95 grooves of the spindle, a nut upon the spindle adapted to hold the hub in place, and a cup-shaped sand-band disposed with its edges within the groove in the outer end of the hub 100 and lying within the inclosure of the band upon the hub to which it is attached.

In testimony that I claim the foregoing as my own I have hereto affixed my signature in the presence of two witnesses.

WALTON A. EDDY.
